MACHINE FOR APPLYING TREATMENT SOLUTION OVER LIMITED AREAS OF MOTION-PICTURE FILM

Harold L. Fitch and Stanley L. Scudder, Rochester, N. Y., assignors to Eastman Kodak Company, Rochester, N. Y., a corporation of New Jersey

Application June 23, 1950, Serial No. 170,006

6 Claims. (Cl. 95—94)

1

This invention relates to photography and more particularly to a device for applying a band of solution to motion-picture film. One object of our invention is to provide a solution-applying device capable of applying a band of solution to an edge of motion-picture film and capable of producing a sharp edge to the stripe of solution so applied. Another object of our invention is to provide a machine of the class described in which a capillary blade applies a layer of solution through capillary attraction along an edge or a portion of a motion-picture film. A still further object of our invention is to provide a machine in which a motion-picture film may be supported in an arcuate path and to provide a curved blade for accurately defining an area of the film to be coated with solution. Other objects will appear from the following specification, the novel features being particularly pointed out in the claims at the end thereof.

In motion-picture processing machines, it is frequently necessary to apply a film treatment solution or to apply tinting, toning or other solutions to predetermined areas of film. In motion-picture film having a sound record on one edge, it is particularly desirable to apply a layer of solution such as sodium sulfide to the sound track, particularly where the film is a color film and where it is desirable to produce a silver image in the sound track before passing the film on to various fluid treatment and color-forming operations. While it is obvious that our solution applicator may be used for applying any solution in the form of a band or strip upon a moving motion-picture film, it is nevertheless particularly adapted for applying a band of solution to one edge of a moving film for the purpose of treating a sound track.

Coming now to the drawings wherein like reference characters denote like parts throughout

Fig. 1 is a prospective view of a device for applying a band of solution to one edge of a motion-picture film constructed in accordance with and embodying a preferred form of our invention.

Fig. 2 is a prospective view of the apparatus shown in Fig. 1 taken from a different viewpoint and showing the apparatus with the film-supporting roller and the film removed from the machine to better illustrate portions of the machine.

Fig. 3 is a fragmentary section through the support and a bracket carried by the support which in turn carried the film-supporting drum.

2

Fig. 4 is a fragmentary sectional view showing a portion of the base, the bracket for supporting the film drum and a film guiding spring.

Fig. 5 is a fragmentary section through a portion of the film supporting drum and base showing also the capillary blade and the capillary bead of solution between the blade and the film. This view likewise shows a portion of the fluid container in which the device for applying solution is mounted and

Fig. 6 is a fragmentary view of a film schematically showing the picture areas and the stripe of solution applied to the film.

Our invention consists broadly in a machine having a base supporting a film guiding roller so that an area of film lying about the roller may be coated with a bead of solution drawn up by capillary attraction between a curved blade and the film so that this bead will produce a sharp edge on a stripe of solution on an edge of the film and, in the present instance, of sufficient width to cover the sound track area of the film.

More specifically, our invention consists in a device for applying solution which comprises a base member 1 having an aperture 2 at one end through which a hinge pintle 3 may pass to hinge the base to supporting ears 4 carried by a tray 5 adapted to contain a treating solution 6. The elevation of this treating solution is preferably controlled with a high degree of accuracy but since this control forms no part of the present invention we have schematically shown the level L of the solution to be controlled by an overflow aperture 8 provided in a screw cap 9 which can be turned to vary the position of the aperture 8.

The base 1 is provided with an elevation controlling screw 10 which may be used to hold the base at the desired angle to the bottom 12 of the tray 5 by means of a lock nut 11. There is also affixed to the base an upstanding supporting arm 13 which may be attached by screws 14 or by other suitable means. This arm 13 is formed over at the top 15 and it is provided with a split area 16 so that a set screw 17 may pinch the formed-over portion 15 together to hold a set screw 18 definitely in place. This set screw is provided with a shoulder 19 for pressing downwardly on the upper surface 20 of a U-shaped bracket 21 which is thrust upwardly by a spring 22 encircling a dowel pin 23 extending downwardly from the lower arm 24. Thus the elevation of the U-shaped bracket 21 can be adjusted by turning the set screw 18 and clamping it in place when properly adjusted by the set screw 17.

The base also carries a solution-applying blade 25, this blade being arcuate in shape and extending upwardly from a member 26 which is attached to the base in any suitable manner as by screws or rivets 27. The capillary blade 25 may include a guide block 28 having a curved surface 29 to direct film behind the blade 25 but we have found that this block is not necessary and may be omitted if desired. The base may also be provided with a spring 30 extending upwardly, this spring being attached to the base as by screws 31. A spring arm 32 preferably presses against the lower arm 24 of bracket 21 to help retain it in place but this bracket too is not absolutely necessary since it is usually more convenient to guide the bracket by means of the dowel pin 23 and the shaft 33 which is threaded at 34 and which is engaged by the set screw 18. It is of course necessary to construct these parts to locate film as accurately as possible and to prevent vibration.

The film F may be guided by a drum 40 which may take the form of a single flanged roller as shown in the drawings. The drum 40 has a pair of spaced film supporting surfaces 41 and 42 over which there is a flange 43. It is also provided with cone-shaped trunnions 44 and 45, the upper one of these trunnions being adapted to engage a V-shaped recess 46 in the end of a screw 47 which is adapted to move in a mating thread in the upper arm 48 of the bracket 21. This screw may be adjusted by a knurled head 49 and a set screw 50 may be employed to hold the screw in an adjusted position.

The lower arm 24 of the U-shaped bracket 21 is equipped with a pad 51 having a V-shaped notch 52 therein to receive the lower trunnion 45 of the drum 40. This pad 51 may be constructed of resilient material such as rubber, Koroseal or the like or it may be made of a pad of nylon. In any event, the freedom of movement of the roller 40 may readily be controlled by the position of the screw 46 and by applying more or less axial pressure to the film supporting drum, it can be made to move with considerable freedom or it may be materially retarded according to the needs of the particular setup.

In use, a film band F may be brought at an angle into the tray 5 and may be looped about the film support drum 40 so that the spring 30 as shown in Fig. 1 may press the film edge upwardly and into intimate contact with the flange 43. It is generally desirable to bring the film into the pan 5 at a slight angle as indicated in Fig. 5 so that the film may pass from suitable guides, not shown, beyond the end of the pan and over the flange of the pan as it passes towards and from the supporting drum 40. It may be noted that the level L of the solution lies below the bottom edge of the film in Fig. 5. We have found that the distance above the level of the coating solution is not critical but it may be in the order of $\frac{1}{16}$ of an inch plus or minus $\frac{1}{32}$ of an inch. However, the film is immediately wetted with a solution 6 because of a meniscus of the solution against the blade 25 and as the film moves a capillary bead B is formed between the film and the inner surface of the blade 25 so that a smooth and even stripe of solution is applied as the film passes to and from the supporting drum 40. It will be noted that the applying blade 25 extends a material distance around the film supporting drum 40 as, for instance, 170° , so that a narrow bead B of considerable length is in contact with the film thereby making it possible

to treat a limited area of the film with an accurately formed band of solution.

The thickness of the film bead is important because if the spacing between the blade and the film is too great, a bead will not form. We prefer to have a spacing between the blade and the film supporting drum of approximately .012 or .013 inch so that with a film normally .007 inch in thickness in which because of the treatment baths, the thickness may be swollen to .008 inch, the spacing between the film and the blade may be .005 inch or somewhat less than the thickness of the film. These figures are given by way of example only and it is obvious that they may be varied to suit the operation being performed.

Referring to Fig. 6 schematically showing a film F, it will be noticed that in this embodiment, the film is provided with apertures A and picture areas P. In this instance, the apertures are omitted from the lower edge of the film since this area is used for a sound track and the area S indicates the area which has been treated with treatment solution.

In initially setting up the machine, the tray 5 is mounted on an accurately aligned table and the base 1 may be adjusted to the proper angle by means of the set screw 10. If the base is hingedly attached to the tray by a pintle 3, the base will turn on this pintle in reaching its set position. The hinged pintle 3 may be omitted in which case the base will merely rock about the left-hand end with reference to Figs. 1 and 5 until the proper angle is reached to clear the film F of the tray in passing to and from the tray. The end of the film F is then passed over the spring 30 and over the pads 41 and 42 on the supporting drum 40 and is moved outwardly to guide rollers not shown so that when the film is moved by any suitable mechanism, the film band will be drawn in a smooth arc around the inside of the blade 25 and will be spaced from the blade a short distance. A capillary bead B will be formed so that as the film continues to move on the moving drum 40, a band of solution will be drawn out over the lower area of the film in the present embodiment as indicated at S in Fig. 6.

As above pointed out, this machine may be used for purposes other than applying a solution such as sodium sulfide to the sound track of a color film and it may well be found convenient for applying stripes of various width to films as for tinting, toning, treating or the like.

While we have described an embodiment of our invention which is suitable for carrying out the several objects of our invention and one which is well adapted to meet the conditions of practical use, it is obvious that other forms may readily occur to those skilled in the art. It is to be understood that all the matter herein set forth or shown in the accompanying drawings, is to be interpreted as illustrative only and not in a limiting sense.

We claim:

1. A device for applying a band of solution to a moving band comprising a base, a tray to receive the base and adapted to hold a treatment solution at a desired elevation, a screw for adjusting the base in the tray to vary the angle of the base to that of solution contained in the tray, a bracket carried by the base having bearings therein, a drum having trunnions revolvably supported by the bearings of the bracket, an arm extending upwardly from the base and slidably carrying the bracket, adjustable means for sliding the bracket

relatively to the arm, a curved solution applying blade mounted on the base and having a position approaching but lying out of contact with the drum whereby the relationship of the moving band carried by the drum may be varied with respect to the solution applying blade by moving the bracket on the arm and thereby moving the band transversely of the solution applying blade.

2. The device for applying a band of solution to a moving band defined in claim 1, characterized in that a band carried by the drum may be above the surface of solution in the tray while only a portion of the solution applying blade lies close to but spaced from said band carried by the drum to produce a stripe of solution on the band as the drum rotates.

3. The device for applying a band of solution to a moving band defined in claim 1, characterized in that a band carried by the drum may be above the surface of solution in the tray while only a portion of the solution applying blade lies close to but spaced from said band carried by the drum to produce a stripe of solution on the band as the drum rotates and a beveled edge on the curved solution applying blade defining the edge of the stripe of solution applied to the band.

4. The device for applying a band of solution

to a moving band defined in claim 1 characterized in that the distance between the band and the solution carrying blade is less than the thickness of that of the moving band.

5. The device for applying a band of solution to a moving band defined in claim 1 characterized in that the distance between the solution applying blade and the drum being substantially twice that of the thickness of band of material to be treated.

10 6. The device for applying a band of solution to a moving band defined in claim 1 characterized in that there is a spring arm mounted on the base and tending to move upwardly therefrom and adapted to engage an edge of the band moving with the drum to be treated with solution.
